(57) **CLAIM**

The ornamental design for a pen, as shown and described.

DESCRIPTION

FIG. 1 is a perspective view of a pen according to a first embodiment showing my new design;

FIG. 2 is a front view thereof, a rear view being a mirror image;

FIG. 3 is a left side view thereof;

FIG. 4 is a right side view thereof;

FIG. 5 is a top view thereof;

FIG. 6 is a bottom view thereof;

FIG. 7 is a front view of a cap thereof, shown without the body for convenience; a rear view of the cap being a mirror image;

FIG. 8 is a left side view of the cap thereof;

FIG. 9 is a right side view of the cap thereof;

FIG. 10 is a top view of the cap thereof;

FIG. 11 is a bottom view of the cap thereof;

FIG. 12 is a front view of a body thereof, shown without the cap for convenience; a rear view of the body being a mirror image;

FIG. 13 is a left side view of the body thereof;

FIG. 14 is a right side view of the body thereof;

FIG. 15 is a top view of the body thereof;

FIG. 16 is a bottom view of the body thereof;

FIG. 17 is an exploded perspective view thereof;

FIG. 18 is a perspective view of a pen according to a second embodiment showing my new design;

FIG. 19 is a front view thereof, a rear view being a mirror image;

FIG. 20 is a left side view thereof;

FIG. 21 is a right side view thereof;

FIG. 22 is a top view thereof;

FIG. 23 is a bottom view thereof;

FIG. 24 is a front view of a cap thereof, shown without the body for convenience; a rear view of the cap being a mirror image;

FIG. 25 is a left side view of the cap thereof;

FIG. 26 is a right side view of the cap thereof;

FIG. 27 is a top view of the cap thereof;

FIG. 28 is a bottom view of the cap thereof;

FIG. 29 is a front view of a body thereof, shown without the cap for convenience; a rear view of the body being a mirror image, a top and bottom views of the body being identical to the front view;

FIG. 30 is a left side view of the body thereof;

FIG. 31 is a right side view of the body thereof; and,

FIG. 32 is an exploded perspective view thereof.

(Continued)

The broken lines showing the inside in FIG. 9 are included for the purpose of showing a portion of the pen that forms no part of the claimed design.
